UNITED STATES PATENT OFFICE.

JOHN BELL SHELTON, OF SAN FRANCISCO, CALIFORNIA, ASSIGNOR TO THE SHELTON
ADJUSTABLE DOUBLE DECK CAR CO., OF SAN FRANCISCO, CALIFORNIA.

COMBINED FREIGHT AND STOCK CAR.

1,205,674.

Specification of Letters Patent. Patented Nov. 21, 1916.

Application filed February 16, 1916. Serial No. 78,559.

To all whom it may concern:

Be it known that I, JOHN BELL SHELTON, citizen of the United States, residing at San Francisco, county of San Francisco, 5 State of California, have invented a certain new and useful Improvement in Combined Freight and Stock Cars, and declare the following to be a full, clear, and exact description of the same, such as will enable 10 others skilled in the art to which it pertains to make and use the same, reference being had to the accompanying drawings, which form a part of this specification.

My invention relates to a combined freight 15 and stock car shown in the accompanying drawings and more particularly pointed out in the following specification and claims.

Among the objects of the present invention is an improvement in the general construction of the adjustable platform, and 20 means for supporting the same, the depth or thickness of the platform being materially reduced over structures of a similar character; while the rigidity and strength 25 of its construction is materially increased.

One of the objects of the invention is to construct the frame of the adjustable deck with a plurality of longitudinal channel irons and I-beams, connected by suitable 30 cross members, and transverse metallic strips, to which are bolted cross timbers to receive a longitudinally arranged flooring spiked thereto, upon which is nailed a flooring consisting of boards transversely laid.

Another object of the invention is to provide a plurality of platform or deck supports mounted in the deck frame and adapted to be projected from each side of the deck, so as to overlap the usual longitudinal strips forming the walls of a stock car, 40 to support the deck in its elevated position. In place of the usual wooden strips, however, iron bars may be attached to the upright members of the car frame to receive 45 the overlapping projecting ends of the deck supports.

Another feature of the invention consists in connecting these several supporting de-

vices into groups, whereby two or more may be simultaneously operated:—means being 50 also shown to support the deck by devices pivoted to a suitable casting bolted to the upright members of the car frame and which are likewise connected in groups to be simultaneously operated to support the plat- 55 form.

Another feature of the invention consists in providing relatively long traveling beams, to which are attached cables for raising the adjustable platform or deck, mounted upon 60 a right and left screw-threaded shaft in turn supported by suitable hangers from the roof frame:—means being provided for manually rotating the shaft, that the traveling beams may be actuated toward each other, 65 or in opposite directions to raise or lower the deck.

One of the features of the present construction consists in providing traveling beams of a length practically equivalent to 70 the width of the interior of the car, that the hoisting cables attached to the ends of the beam may be supported by sheaves attached to the side walls of the car frame intermediate of its ends, instead of employing 75 relatively short beams requiring cables of sufficient length to reach the ends of the car as has been the usual practice. The cables are thus comparatively short and correspondingly less expensive, and being connected to the platform midway of its ends, 80 there is less liability of the platform sagging under its load.

Another feature of the invention consists in means carried by the rotatable shaft to 85 provide against end thrust of the latter:—the means in the embodiment shown consisting of suitable collars secured to the rotatable shaft adapted to bear against the hangers for supporting the latter. 90

Another feature of the invention consists in providing means for preventing the spreading of the longitudinal frame members of the adjustable platform.

Another feature consists in providing 95 means for preventing the spreading of the

plates between which the ratchet wheel of the lever employed for operating the rotatable shaft is mounted.

Other advantages and improvements will 5 hereafter appear.

In the drawings accompanying this specification:—Figure 1 is an elevation of a car with one portion in longitudinal section, showing the adjustable platform raised to 10 form a double deck stock car. Fig. 2 is a plan view of the roof framing showing the rotatable shaft and traveling beams supported thereby, and the sheaves for carrying the cables bolted to the side members of the 15 car frame. Fig. 3 is a plan view of the adjustable deck with parts broken away to more clearly disclose its construction. Fig. 4 is a cross sectional view through the car showing the deck raised and the supporting 20 devices adjusted to overlap the longitudinal side rails of the car walls. Fig. 5 is a similar cross sectional view with the supporting devices withdrawn, and the deck lowered to the floor of the car. Fig. 6 is a diagrammatic plan view of the car body and the 25 adjustable deck with parts in section, showing the deck supporting device withdrawn from engagement with the rails on one side of the car, as when the deck is lowered;—the 30 opposite side showing the supporting devices engaged with the longitudinal side rails of the car wall as they would appear when the platform was raised to form a double deck car. Fig. 7 shows a detail with 35 parts in elevation and section, of a modification of the means for supporting the adjustable deck. Fig. 8 shows the device indicated in Fig. 7 raised out of the path of the platform that the latter may be lowered to the 40 floor of the car. Fig. 9 is a plan view of the device indicated in Fig. 7 secured to one of the posts (in section) of the car frame, showing a fragment of the rail connecting the devices together, that they may be simultaneously operated. Fig. 10 is an elevation 45 of the device shown in Fig. 7 attached to a fragment of the car frame looking at the device from the inside of the car. Fig. 11 is an elevation of the ratchet lever showing the 50 overlapping lip of the plate carried by the lever, between which the ratchet wheel is mounted. Fig. 12 is a view of the lever at right angles to Fig. 11.

Referring now to the letters of reference 55 placed upon the drawings:—A, denotes a freight car; B, a relatively short right and left screw-threaded shaft extending longitudinally within the car and supported by suitable hangers B', secured to the roof 60 timbers C.

B², indicates a ratchet lever for manually actuating the shaft.

b, b, are plates bolted to the operating le-

ver, between which is journaled a ratchet wheel b', actuated by a suitable dog b²;— 65 and to insure against spreading of the plates b, b, in operation, a hook-shaped portion b³, is formed integral with one of the plates and adapted to overlap its opposing plate, as indicated in Fig. 12.

b³, b³, denote collars on the shaft B, to 70 secure the shaft against end thrust.

D, and D', are long traveling beams, carried by the right and left screw-threaded portions of the shaft B;—extending from 75 the shaft to each side of the car, the ends of the beam being fitted with eye bolts or other means for securing hoisting cables thereto.

E, E, and E', E', are hoisting cables secured to the ends of the respective beams 80 D, D', supported by sheaves F, bolted to the side walls of the car.

G, indicates an adjustable deck, to which the respective cables E, E', are connected by hoisting brackets g, bolted to the sills of the 85 deck. The deck G, comprises a rectangular frame H, constructed of channel irons H', forming its side sills;—connected together at their ends by angle irons H².

I, I, are longitudinally arranged I-beams 90 bolted to the angle irons H², of the rectangular frame H.

J, J, denote metallic strips bolted to the under side of the sills H', and to the intermediate longitudinal I-beams of the rec- 95 tangular frame H.

K, indicate cross timbers bolted to the re- 99 spective strips J.

L, are longitudinally arranged floor 100 boards spiked to the cross timbers K;— and M, are transverse floor boards nailed to the longitudinal boards I, beneath.

M', are filler blocks for the door way of 105 the car, bolted to the channel irons H'.

N, is a centrally located brace rod extending beneath the intermediate I-beams, with 110 its threaded ends projecting through openings in the side channel irons H', the ends being threaded to receive nuts N', to secure the channel irons against spreading.

O, denotes a plurality of slidable bolts 115 projecting through apertures provided for their reception in the channel irons sills and the intermediate I-beams, said bolts being adapted to be manually projected beyond the sides of the platform to overlap the rails P, of the car wall.

O', indicates a bar connecting two or 120 more of the bolts together, whereby they may be simultaneously actuated.

The outer end of the bolts O, are pref- 125 erably provided with a hooked portion O², designed to engage the rails P, to insure against accidental withdrawal of the bolts due to the jar incident to the movement of the car.

O^o, are stops, which may or may not be employed to limit the maximum movement of the bolts.

In Figs. 7 to 10 are shown a modification 5 of the means for supporting the deck when elevated, comprising a casting Q, bolted to the upright members of the car frame.

R, is a swinging hooked deck support pivoted at r, to the casting Q. The rear 10 end of the swinging deck support R, bears upwardly against the overlapping portion q, of the casting, indicated in Fig. 9, while the forward portion of the deck support on the opposite side of its pivot bears down- 15 wardly upon the portion q', of the casting Q, beneath the deck support,—as indicated in Fig. 10, when the device is in position (see Fig. 7) to receive and support the deck.

R', is a rail bolted to the respective deck 20 supports R, to provide for simultaneous manual operation of two or more of the supporting devices.

Having indicated the several parts by reference letters, the construction and operation 25 of my invention will be readily understood. When employed as an ordinary freight car, the adjustable deck rests upon the floor of the car. To adapt the car for carrying small stock, the adjustable deck 30 is raised by the rotation of the shaft through the manual operation of the ratchet lever. The traveling beams, to which the platform is secured by the cables are thus drawn toward each other, thereby raising 35 the platform as will be readily understood. When elevated to the height desired, the platform supporting bolts are forced outwardly that they may overlap the side rails of the car wall.

40 Instead of supporting the platform upon the usual side rails forming the side walls, angle irons or other metallic members may be bolted to the walls to receive the supporting bolts, as previously explained. The 45 platform is thus securely held until it is again desired to employ the car for carrying ordinary freight, when the supporting devices are withdrawn and the deck lowered to the floor of the car by a reverse operation 50 of the ratchet lever.

The construction of the adjustable deck shown in the present embodiment has enabled me to reduce its thickness;—thereby increasing the carrying capacity of the car 55 and materially adding to the strength of the platform.

By providing traveling beams extending 60 from side to side of the car and connecting the latter with the platform intermediate of its length, I insure the platform against sagging under its load, while the cost of the hoisting cable is materially reduced. By mounting the deck supports beneath

the movable platform, they are protected against injury when the car is used for 65 shipping ordinary freight;—the deck affording protection from contact therewith.

I do not wish to limit myself to a deck supporting device carried by the platform, as it is obvious that other means adapted 70 for simultaneous manual operation may be employed, as for example the modification shown in Figs. 7 to 10 of the drawings.

Having thus described my invention, 75 what I claim is:—

1. In a car, a rotatable shaft located within the car having right and left screw-threaded portions, a traveling beam extending from side to side of the car fitted to each screw-threaded portion of the shaft, a movable platform adapted to rest upon the floor of the car when not in use, cables connecting the ends of the traveling beams with the sides of the platform intermediate of its length, a plurality of sheaves bolted to the 80 side walls of the car for supporting and guiding said cables, and manually actuated means carried by the shaft adapted to rotate the latter in either direction, whereby the platform may be raised or lowered. 90

2. In a device of the character described, a movable platform, a plurality of slidable bolts carried by the frame of the platform adapted to be projected beyond the edge of the platform into engagement with the walls 95 of the car, whereby the platform may be supported when adjusted, and means connecting two or more of the slidable bolts together, whereby they may be simultaneously and manually actuated. 100

3. In a car, a rotatable shaft located within the car, traveling beams extending from side to side of the car and fitted to the rotatable shaft, a movable platform, cables connecting said traveling beams and the 105 sides of said platform intermediate its length, and means for rotating said rotatable shaft to raise or lower said platform.

4. In a car, a rotatable shaft, located within the car, traveling beams extending 110 from side to side of the car and fitted to the rotatable shaft, a movable platform, cables connecting said traveling beams and the sides of the platform intermediate its length, means for rotating said rotatable 115 shaft to raise or lower said platform and means carried by the platform for supporting it in any adjusted position.

5. In a car, a rotatable shaft located within the car having right and left screw 120 threaded portions, a traveling beam extending from side to side of the car fitted to each screw threaded portion of the shaft, a movable platform, cables connecting the ends of the traveling beams with the sides of the 125 platform intermediate its length, means for

rotating the rotatable shaft and thereby raise and lower said platform and means carried by the platform for supporting it in any adjusted position.

5 6. In a car, a rotatable shaft located within the car, traveling beams mounted on the rotatable shaft and extending from side to side of the car, a movable platform, means connecting the platform and the 10 traveling beams, means for rotating the rotatable shaft and thereby raising or lowering said platform and a plurality of sliding bolts carried by the platform for supporting it in any adjusted position, and means for 15 operating said sliding bolts in unison.

7. In a car, a movable platform therein, means for supporting said platform when adjusted, comprising a plurality of slideable bolts supported in the platform, said bolts having hook-shaped ends adapted to engage the sides of the car and support said platform in its adjusted position, and means connecting a plurality of said bolts together whereby they may be operated in unison. 20

In testimony whereof, I sign this specification in the presence of two witnesses.

JOHN BELL SHELTON.
